US00D621393S

(12) **United States Design Patent**
Panahi et al.

(10) **Patent No.:** US D621,393 S
(45) **Date of Patent:** ** Aug. 10, 2010

(54) **PORTION OF A PROTECTIVE CASE**

(75) Inventors: **Michael Panahi**, Englewood, NJ (US);
Wei He, Fujian (CN)

(73) Assignee: **IvySkin LLC**, S. Hackensack, NJ (US)

(**) Term: **14 Years**

(21) Appl. No.: **29/329,464**

(22) Filed: **Dec. 16, 2008**

(51) **LOC (9) Cl.** 14-03

(52) **U.S. Cl.** D14/250; D13/103

(58) **Field of Classification Search** D14/140,

(74) *Attorney, Agent, or Firm*—Steven N. Fox, Esq.

(57) **CLAIM**

The ornamental design for a portion of a protective case, as shown and described.

DESCRIPTION

FIG. 1 is a bottom perspective view of the design according to the present invention;

FIG. 2 is a rear elevation view of the design according to the present invention;

FIG. 3 is a right side elevation view of the design according to the present invention;

FIG. 4 is a bottom plan view of the design according to the present invention;

FIG. 5 is a front elevation view of the design according to the present invention;

FIG. 6 is a left side elevation view of the design according to the present invention; and,

FIG. 7 is a top plan view of the design according to the present invention.

In the drawing, the broken lines depict unclaimed environment.

1 Claim, 3 Drawing Sheets
